SPOOL HOLDER

Richard J. Gollong, Johnson City, Tenn., assignor
to American Glanzstoff Corporation, New York,
N. Y., a corporation of Delaware

Application April 1, 1932, Serial No. 602,584

2 Claims. (Cl. 242—46.6)

My present invention relates to improvements in spool holders and more particularly to those types of holders adapted primarily for use in the manufacture of artificial silk.

5 In the manufacture of artificial silk and the like a suitable cellulosic solution is spun into a coagulating medium and then collected on spools. Each spool is mounted on a spool holder secured to a rotatable shaft, and the thread is laid thereon by leading the same over a reciprocating or oscillating guide. Since the thread is usually spun into a coagulating bath of acid reaction, the spool holders now in use are readily attacked by the liquid of said bath resulting in the necessity of a frequent replacement of the spool holders. Many types of spool holders are known to the trade which have been designed to overcome this difficulty. The use of aluminum spool holders has been proven to be unsatisfactory since 10 the aluminum is dissolved by the acid of the coagulating bath and causes the formation of aluminum spots on the yarn when dyed. The use of other metals has been suggested but these are open to the same objections or are impracticable 15 to use on a commercial scale.

It is therefore an object of my present invention to provide a new type of spool holder which will obviate the above difficulties.

It is another object of my invention to provide 20 suitable means for clamping the spool to the spool holder and at the same time be of such a construction that the same may be readily replaced when worn or otherwise rendered unfit for further service.

25 These and other objects of my present invention will become more apparent from a study of the following description and by reference to the accompanying drawing in which:

Figure 1 is a section view of my new spool holder on the line 1—1 of Figure 2 showing the same secured to the spool shaft;

Figure 2 is a top-plan view thereof; and

Figure 3 is a detailed view of the spool holding means.

40 Referring now more particularly to the drawing, I have disclosed thereon a preferred form of my invention. The base 10, made of hard rubber or other acid resistant material, is provided with a centrally located bore 11 adapted to receive the blade 12 of the spindle (not shown). This blade is threaded on its outer end and the spool holder is secured thereto by any convenient locking means as by nut 13, and is provided with a shoulder 12' against which the base is 45 held by the said nut. It is imperative to insure

a perfect rotation of the spool during the spinning operation that the bore be located centrally of the base.

Formed integrally with the base is an upwardly extending hollow substantially cylindrical body 60 member 14, the circumference of which is less than that of the base thus providing a suitable seat 15 for the end of the spool 16. A plurality of rectangular slots 17, preferably three in number, are formed in the wall of the hollow cylindrical member adjacent the outer end thereof and are adapted to receive the spool locking means.

The locking means, shown in detail in Figure 3, each consists of a substantially rectangular 70 member 18 cut away at 19 to form a shoulder 20 to limit the movement of same locking means in the slot provided therefor in the hollow cylindrical member 14. The outer end 21 of the locking member is wing shaped and the lip of each wing 75 is formed of stiff rubber. Since the inner end of each locking member is larger than the slot in the cylindrical member within which it fits, I have provided a slot or cut-out portion 22 so that the furcations thus produced may be bent toward 80 each other sufficiently to permit insertion thereof in the slot in the cylindrical member.

In operation each of the slots in the cylindrical member is provided with one of these locking or holding members. The spool is then forced over 85 the latter flattening the wing portions as indicated in dotted lines in Figure 2. This causes the holding means to be pressed against the inner walls of the spool with sufficient force to hold the said spool securely on the spool holder. 90

From the above description it will readily be appreciated that I have provided a novel type of spool holder the construction of which is such as to render the same resistant against acids contained in the spinning or coagulating bath. 95 Moreover the device is constructed of few parts which are of such a character that should any one of them become damaged it may readily be replaced without necessitating the discarding of the entire assembly.

Although I have described in detail the preferred form of my invention, it is obvious that many modifications in the construction thereof may be made without departing from the spirit of my invention or the scope of the appended claims. 105

What I claim as new is:

1. In a spool holder comprising an opening formed therein adapted to receive a spindle blade; means to hold a spool thereon comprising a hollow member extending upwardly from said base 110

and having a plurality of spaced openings formed therein, holding means having wing shaped outer ends secured in said openings, said outer wings having hardened tips of acid resisting material 5 adapted to bear resiliently against said spool.

2. In a spool holder comprising a base having an opening formed therein adapted to receive a spindle blade; means to hold a spool thereon comprising a hollow member extending

10

upwardly from said base and having a plurality of spaced openings formed therein, holding means having wing shaped outer ends secured in said openings adapted to bear resiliently against said spool, the inner ends thereof being bifurcated and shouldered to limit the outward movement of said members in said openings.

RICHARD J. GOLLONG.
